US00D908909S

(12) **United States Design Patent** (10) **Patent No.:** **US D908,909 S**
(45) **Date of Patent:** **** Jan. 26, 2021**

(54) **SEX TOY**

(71) Applicant: **SHILOSH (SHENZHEN) TECHNOLOGY CO., LTD.**, Shenzhen (CN)

(72) Inventor: **Minyi Huang**, Shenzhen (CN)

(73) Assignee: **SHILOSH TECHNOLOGY (SHENZHEN) CO., LTD.**, Shenzhen (CN)

(**) Term: **15 Years**

(21) Appl. No.: **29/735,745**

(22) Filed: **May 22, 2020**

(51) **LOC (13) Cl.** **28-03**

(52) **U.S. Cl.** **USPC** **D24/215**

(58) **Field of Classification Search**

USPC D24/200, 211, 212, 213, 214, 215
CPC A61H 19/44; A61H 2201/0153; A61H 2205/087; A61H 19/34; A61H 19/30

See application file for complete search history.

(57) **CLAIM**

The ornamental design for a sex toy, as shown and described.

DESCRIPTION

FIG. 1 is a front, right side, top perspective view of a sex toy showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the sex toy that form no part of the claimed design.

1 Claim, 8 Drawing Sheets
